CLAIM

The ornamental design for a massage appliance, as shown and described.

DESCRIPTION

1. Massage appliance

Figure 1.1 is a perspective view of a massage appliance;

Figure 1.2 is a front view thereof;

Figure 1.3 is a back view thereof;

Figure 1.4 is a left view thereof;

Figure 1.5 is a right view thereof;

Figure 1.6 is a top view thereof; and

Figure 1.7 is a bottom view thereof

The broken lines shown in Figure 1.7 illustrate portions of the massage appliance that form no part of the claimed design. The dash-dot lines shown in Figure 1.7 illustrate a boundary and forms no part of the claimed design.

1 Claim, 7 Drawing Sheets
